UNITED STATES PATENT OFFICE.

SUMMERS BROWN, OF LONDON, ENGLAND.

FLEXIBLE STRIP-FORM FOR HOLDING TYPE.

No. 876,522.

Specification of Letters Patent.

Patented Jan. 14, 1908.

Application filed July 20, 1907. Serial No. 384,828.

To all whom it may concern:

Be it known that I, SUMMERS BROWN, residing at 40 Whitecross street, London, England, Great Britain, have invented a certain new and useful Improvement in Flexible-Strip Forms for Holding Type; and I do hereby declare the following to be a full, clear, and exact description of the invention, such as will enable others skilled in the art to which it appertains to make and use the same.

My invention consists in a flexible metallic strip or strips for carrying a series of type bars adapted for holding type, and enabling the same to be set up, mounted and secured upon any kind of rotary printing cylinder, the object I have in view being to enable characters, figures, stops or the like to be set up in suitable grooves formed by contiguous type bars, secured to flexible metallic strips upon any convenient surface, and when filled to wrap or otherwise mount and secure the flexible form thus constructed upon any kind of rotary printing cylinder, drum, part of the same or carrier. After the requisite number of copies have been printed the flexible form may be removed from the rotary cylinder drum or drums as the case may be, hung up or stored away for re-use as often as required, or the type or other characters may be distributed.

The way and manner in which I carry out my invention will be understood by reference to the drawing in which:

35 Figure 1. is a side elevation of part of a printing cylinder or drum showing a flexible strip form mounted upon and secured to it. Fig. 2. is a longitudinal elevation of part of a type carrying bar having flexible strip recessed therein, and riveted thereto. Fig. 3. is a plan showing three flexible strips type bars thereon, and type characters mounted in the groove formed by two contiguous bars.

45 In the drawings —a— is the flexible metallic strip formed preferably of thin steel, or like suitable metal; mounted thereon and secured preferably by rivets —d— are a series of type bars —b— grooved on both sides as at —c—. The under part of each type bar —b— is preferably cut away on one side see Fig. 2. as at —e— to enable the type letters to be forced into and removed from the groove more conveniently, although such cutting away may be dispensed with, as shown in Fig. 1. The type-characters *f* are

so grooved as at —f— as that while they engage with the grooves formed by the contiguous type bars, they can be easily slid along therein. To enable the flexible strip 60 riveted to the type bars to be clear of the surface of the cylinder, so that said bars may sit firmly thereon, I form a series of grooves —g— and recess and rivet said strip or strips thereto. In the plan Fig. 3. I have 65 shown three such strips —a— with type bars —b— thereon and type characters —f— mounted in the groove —f— formed between two contiguous bars. To secure the strip to the cylinder or drum, —h— I perforate the same at both ends in the manner shown at —h— and insert a hook —i— forming part of the wire springs —i'— in each of said holes, the opposite ends of said springs being formed with a hook —i— and secured 70 to a metallic peg or pin —j— driven into the barrel. This forms an elastic mount and keeps the form in its true position. The form described is first set up in any convenient position, and is then removed, mounted 75 upon and secured to the cylinder or drum in the manner shown.

It will be understood that I may modify the make up and fastening of the type bars to the flexible strip to suit the varying 85 conditions demanded by printing cylinders, drums and the like.

Having thus described my invention, what I claim as new and desire to secure by Letters Patent is:

1. In combination with a rotating printing cylinder or carrier, a series of flexible metallic strips, type-holding bars attached to said strips and composing with them a flexible form, type-characters fitting into the intervals between said bars and held therein and means for flexibly securing said form to said cylinder substantially as set forth. 90

2. In combination with a rotary printing cylinder or carrier, a series of flexible metallic strips, a series of transverse type-holding bars, grooved in their sides, fastened to said strips at intervals and composing therewith a flexible form and type characters fitting into the intervals between said bars and interlocking with them by lateral grooves and projecting parts substantially as set forth. 100

3. In combination with a rotary printing cylinder or carrier, a series of flexible strips, a series of transverse type-holding bars fastened at intervals thereto and constituting a flexible type-holding form therewith, holding springs 110

engaging the ends of said strips and studs on the cylinder engaging the said springs substantially as set forth.

4. In combination with a rotary printing cylinder or carrier, a series of flexible metallic strips, a series of transverse type-holding bars fastened at intervals thereto and constituting a flexible type-holding form therewith, means for attaching said form to said cylinder, and type-characters fitting into the intervals between said bars and into grooves in their sides substantially as set forth.
- 10 5. A flexible printing form consisting of

strips and bars arranged transversely to each other and leaving intervals of proper width 15 to receive type-characters, the said bars being adapted to engage and hold such characters before the said form is applied to the cylinder substantially as set forth.

In witness whereof, I have hereunto signed 20 my name in the presence of two subscribing witnesses.

SUMMERS BROWN.
